(57) **CLAIM**

The ornamental design for a "clothes hanger body," as shown and described.

DESCRIPTION

FIG. 1 is a front perspective view of a clothes hanger body showing my new design, the rear perspective view being identical thereto;

FIG. 2 is a front elevational view thereof, the rear elevational view being identical thereto;

FIG. 3 is a left side elevational view thereof, the right side elevational view being identical thereto;

FIG. 4 is a top plan view thereof;

FIG. 5 is a bottom plan view thereof;

FIG. 6 is a front perspective view of a slightly modified form of the design;

FIG. 7 is a front perspective view of a second modified form of the design;

FIG. 8 is a front elevational view of the second modified form;

FIG. 9 is a left side elevational view of the second modified form, the right side elevational view being identical thereto;

FIG. 10 is a top plan view of the second modified form; and,

FIG. 11 is a bottom plan view of the second modified form. The material shown in phantom in the figures is for environment only and does not form a part of the design.
